ASSIGNORS TO HAMILTON CASSARD, OF BALTIMORE, MARYLAND.

BROOM-SEWING MACHINE.

1,071,332.

Specification of Letters Patent. Patented Aug. 26, 1913.

Application filed January 16, 1908. Serial No. 411,176.

To all whom it may concern:

Be it known that we, CHARLES E. OYLER and JOHN HENRY PARKER, citizens of the United States, residing in the city of Baltimore, State of Maryland, have invented certain new and useful Improvements in Broom-Sewing Machines, of which the following is a specification.

This invention relates to improvements in broom sewing machines and will be described in connection with the accompanying drawings, in which:

Figure 1 is a perspective view of a broom sewing machine having the present invention applied thereto; Fig. 2 is an end elevation of a portion of the machine, on an enlarged scale; Fig. 3 is a side elevation of the upper part of the vise and the devices for controlling the step-by-step movements 20 of the vise; Fig. 4 is a side elevation of the vise and the means for controlling the vertical adjustment of a broom therein; Fig. 5 is a detail view of the rack controlling the vertical movements of the broom holder and 25 its connection with the broom holder; Figs. 6 and 7 are detail views of parts of the means for automatically varying the length of the step-by-step movements of the vise; Figs. 8 and 9 are detail views of the looper, 30 or needle threading device, employed; Fig. 10 is a view illustrating the action of the looper in threading a needle.

The present machine is generally similar to that illustrated and described in the U. S. Letters-Patent No. 825,402, dated July 10, 1906, and therefore it is not considered necessary to describe in detail all the parts of the machine but merely those to which the present invention relates.

Like the machine of the patent the present one includes a frame 1 having a suitable top plate 2, and a broom supporting vise comprising two pivotally mounted jaws 3. Within the vise jaws is arranged a vertically adjustable broom support or carrier and the vise is moved step by step by suitable means. The thread 4 is drawn through the broom by needles 5 reciprocated by levers 6 connected with the needles and actuated as described in said patent. The thread is properly positioned to be engaged by the needle hooks by means of the loopers or thread carriers each of which comprises a body 7 pivotally supported upon the frame 55 of the machine and having an aperture therein, through which the needle is adapt-

ed to pass. The looper body 7 is slotted and in said slot is mounted a swinging arm 9. A spring 9^a connecting said arm with the body of the looper acts to hold the arm 60 across the eye 8 in position to grip the thread as shown in Figs. 1 and 8. As the looper is rocked downward from the position represented in dotted lines in Fig. 3, by means hereinafter described, a tail piece 65 10 on the arm 9 contacts with a stationary pin or stud 11 and the arm 9 is thereby prevented from moving farther with the looper and is held in the position shown in full lines in Fig. 3 in which it offers no obstruction to the free passage of the needle 5 through the eye 8. To positively limit the extent of movement which the looper can have in either direction, a pin 7^a is connected with the spindle thereof and a stationary stop 7^b is mounted on the frame. Normally the rocking movements of the looper will not bring the pin 7^a into contact with the stop 7^b but should the looper acquire such momentum as to be carried beyond its ordinary stopping point then said pin will engage the stop and prevent the looper being carried into a position where it might be broken or damaged. The pin 7^a is of such height that it can pass beneath 80 the stud 11. The needle passes through the eye 8 in the looper when the latter is in its lowest or rearmost position represented in full lines in Fig. 3, and as the needle is withdrawn from the broom the looper is 90 rocked upwardly and forwardly so that the arm 9 is caused to extend across the eye 8 and grip the thread between itself and the rear wall of the looper eye as the needle leaves the looper. The two loopers are 95 reversely arranged so that when one is descending or moving toward its lowest position the other is rising, and as shown in Fig. 10, carrying the thread across the body of the opposite needle in rear of the hook or 100 barb thereon so that the thread is positively positioned in rear of the hook and will be drawn through the broom as the needle moves in the opposite direction.

It will be noted that the operation of the 105 looper above described is to lift or carry the thread over and draw it directly into the eye of the needle instead of throwing the thread forward in the direction of the length of the needle, in the manner commonly followed heretofore. That is, with the loopers heretofore employed the thread

has been engaged with the needle eye while being carried in the direction of the sewing already done, or in the general direction of movement of the needle to be threaded. By 5 the present invention, however, the looper is moving backward, or in the direction of the sewing to be done and opposite or against the general direction of the needle movement when the thread is introduced into the 10 needle eye. By the improved looper the needle is positively threaded and there is no chance of the thread slipping from the point or being so positioned as not to be engaged as the needle is drawn backward 15 through the broom.

The looper is rocked in the manner above described by a train of gears 12, one of which is engaged by a rack 13 connected with an arm 14 that extends upwardly from a rock 20 shaft 14^a, a downwardly extending arm 14^b on said shaft having at its lower end a roller 14^c engaging a cam on a suitable disk or cam wheel 15. The vise jaws are moved toward each other to clamp a broom by 25 means corresponding to those described in said patent, including a lever 16, and links 16^a, 16^b connecting such lever and the vise jaws. Means are provided by which the vise jaws may be held in any of several dif- 30 ferent positions, such means including a toothed bar 17 mounted on the vise frame and a coöperating dog 18 carried by a tread- 35 ple 19 which is connected with the lever 16 by means including an adjustable link rod 20 and a connecting bar 21. A spring 22 connecting the treadle or foot lever 19 with a stud on the vise jaw acts to constantly exert a lifting force on said lever. At its lower end the bar 17 is provided with a piv- 40 otally mounted dog 17^a adapted to engage with a stationary stop 23 on the base of the machine at the completion of the outward movement of the vise to release the foot lever or treadle and permit the spring 22, 45 through the connections between the treadle and vise lever 16, to rock the latter to separate the vise jaws and permit the broom support within the vise to fall and bring the broom into position for the next succeeding 50 row of stitches. A spring 17^b holds the dog 17^a in such position that it can yield when passing the stop 23 as the vise is swung inward preliminary to beginning a row of stitches. It will be seen that the lower end 55 of the bar 17 moves in the opposite direction to that in which the upper end of the vise travels. When the vise is in position for the formation of the first of a row of stitches the dog 17^a and stationary stop 23 occupy 60 substantially the relative positions shown in Fig. 4. As the upper end of the vise moves outwardly step by step during the sewing operation the dog is moved toward the stop and at the completion of the row of stitches 65 the engagement between the stop and dog

will cause the upper end of the bar 17 to be moved away from the dog 18, thus releasing the treadle 19 and permitting the vise jaws to separate. The completion of the outward movement of the vise will carry the dog 17^a 70 rearwardly beyond the stop 23, but as the dog is pivotally mounted on the bar 17 it is adapted to yield and offers no obstruction to the return of the parts to the relative positions shown in Fig. 4. 75

The broom support or carrier within the vise is raised to the desired height by the engagement therewith of an arm carried by a foot lever or treadle 24. A rack 25, connected with the broom carrier, and a swing- 80 ing or pivotally mounted dog 26 coöperate to hold the broom carrier in its elevated position and to control the downward movement thereof which is necessary to enable the machine to stitch the broom along dif- 85 ferent lines.

As shown in Figs. 4 and 5, the rack 25 is adjustably connected with the broom support being carried by a hanger 27 having at its upper end a fork the members of which are both provided with laterally extending, vertically separated, lugs 28 which extend respectively above and below a rib 29 on the broom support. The space separating the lugs 28 on the rack hanger is greater than the thickness of the web 29, thus permitting relative vertical movement of the rack and broom support. The space separating the lugs 28 on the rack hanger is greater than 90 the thickness of the web 29, thus permitting relative vertical movement of the rack and broom support. A stud 30 on the pawl 26 extends into a slot at the upper end of a lever 31 pivotally mounted at an intermediate point in its length and having at its lower end an aperture through which extends a rod 32 pivotally connected with the base of the machine. The outer end of said rod 32 is threaded and on it is fitted an 95 adjustable stop 33.

When a broom to be sewed is first placed in the vise the latter is entirely at one side of the path of the needles and the broom support and parts coöperating therewith are 100 in the positions represented in Fig. 4. At this time the broom support is held elevated by the pawl or dog 26 engaging the rack 25, the rib 29 resting on the lower lug 28 of the rack hanger. The vise being closed, by operation of the treadle 19, the broom support will be firmly clamped in its elevated position, although the rack 25 is free to move relative thereto if the dog 26 is disengaged 105 therefrom as hereinafter described. When the vise is swung about its pivotal support 110 to position the broom for beginning a line of stitches, the engagement of the pawl 26 with the lever 31 will rock the latter until the lower end thereof is in contact with the stop 33. This stop is so positioned that it 115 will engage the lever 31 shortly before the vise reaches the position for making the first stitch and as the vise continues to move the rack 25 will be carried away from the 120

pawl 26 and the rack will drop until the upper lugs 28 of its hanger engage or rest on the rib 29. The parts will then be in the relative positions represented in Fig. 5. 5 The frictional engagement between the vise jaws and the broom support or carrier is such that the latter is held stationary and prevented from immediately following the downward movement of the rack. The 10 movement of the rack just referred to is very slight and merely sufficient to allow the pawl 26 to clear the tooth which it formerly engaged. As the vise is moved outward step by step during the sewing operation, 15 the pawl 26 will again be brought against the rack but will occupy a position just above the edge of the tooth previously engaged. After the completion of the row of 20 stitches and when the vise is swung outwardly and the jaws thereof opened, the broom support or carrier will be released and will instantly drop, this downward movement being checked by the pawl 26 engaging the next tooth of the rack and the 25 rib 29 resting on the lower lugs 28. A spring 35 acts constantly to move the pawl into engagement with the rack. This arrangement it will be seen provides for automatically releasing the broom support or 30 carrier and permits it to move downwardly one step at a time following the completion of each line of stitching. It will be noticed that the pawl is released and the rack permitted to move slightly relative to the 35 broom carrier prior to the beginning of a line of stitching and said parts are immediately positioned so as to limit the downward movement of the broom carrier, when the vise is opened, to a single step. With 40 the feeding devices heretofore employed in which the holding pawl was released as the vise was thrown out following the completion of a row of stitches and a spring was depended on to return the pawl to engaging 45 position before the broom carrier could drop more than one tooth, it has been found that occasionally the pawl would not be returned to engaging position sufficiently rapidly and the carrier would fall to a greater distance 50 than was desired.

It will be noted that in the present construction the axis 34 about which the vise rocks is located substantially at the middle of the length of the vise instead of at the 55 lower end as in the construction of the patent referred to. By the present invention the vise closing and broom support adjusting levers 19, 24, are both fulcrumed below the axis about which the vise itself turns. 60 The present invention also includes means for automatically varying the length of the step-by-step motions of the vise during the sewing operation in accordance with variations in the thickness of the broom in the 65 vise. The step-by-step feeding devices, like

those of the machine shown in Patent 825,402, include two feed bars 35, 36, adapted to be alternately clamped by suitable clamping devices controlled by rocker arms 35^a, 36^a, respectively, each of said arms having thereon a roll 37, which rolls are actuated by suitable cams as described in said patent. As described in said patent when the bar 35 is released a spring 38 draws said bar forward until it is arrested by the forward end of an adjustable stop and this movement carries an adjustable pin 40 away from a bracket on the bar 36. A lever 41 fulcrumed on the bracket attached to the bar 36 and connected with the bar 35 acts, 75 when the bar 36 is released and the bar 35 clamped, to shift said bar 36 forward until its end strikes the pin or stop 40.

In the machine of the patent referred to, variations in the length of the stitch are obtained by bodily adjusting a stop limiting the forward movement of the bar 35 or by adjusting the pin 40. According to the present invention however the stop for the bar 35 is made in two sections 42, 43, having 80 opposing cam surfaces and with the section 42 is connected an arm 44. The section 43 is stationarily supported on a tubular extension 45 of a horizontal rod 46 and the inner end of the section 42 is recessed to surround 85 a portion of said extension 45. To provide a firmer support or bearing for the section 42 an extension 47 is attached to the section 43, by a rivet or screw 48 and extends through an axial passage 49 in the section 90 42. To cover the joint between the sections 42, 43 of the stop a sleeve 50 is connected to the section 42, this sleeve being of such length as to inclose the stop section 43 at 95 all times. The arm 44 of the adjustable stop 100 section 42 is connected to one end of a link 51, the opposite end of which is connected by a loose or sliding connection with a bar 52 mounted in a fork at the free end of an arm 53 on a rocking sleeve 54. At its opposite end said sleeve has an arm 55 provided with a pin engaging a slot 56 in a link 57.

A lever 58 pivotally connected at its lower end with the link 57 has its upper arm resting against one of the jaws of the vise 115 and is constantly held in close contact with the vise by the action of a spring 59. When the vise is closed the spring 59 holds the lever 58 and link 57 in the positions shown in the drawing and the parts are so arranged 120 that when the vise is holding a broom of the greatest thickness which the machine is designed to sew the sections 42, 43, of the abutment for the bar 35 will be in the position shown in Fig. 6 and the distance between the 125 end of the bar 35 and said abutment, when the bar 36 is bearing on the pin 40, will be that providing the maximum length of stitch or step-by-step feed movement for the vise. If a thinner broom is inserted in the 130

vise so that the vise jaws are closed to a greater extent than before, the action of the link 57 due to the swinging of the lever 58 by the spring 59, and parts connected therewith will turn the stop section 42 and by the action of the cam surfaces on the meeting faces of the sections 42, 43 said section will be moved longitudinally thus increasing the length of the stop, thereby shortening the distance through which the bar 35 can move when it is released from its clamping means and consequently the length of the stitch will be shortened.

It will be seen that there is thus provided a very simple, automatically acting, mechanism for accurately varying the length of stitch in accordance with the thickness of the broom in the vise.

Having thus described the invention, what is claimed is:

1. In a broom sewing machine, the combination with a broom holder, a needle adapted to be reciprocated through a broom in said holder, and means for effecting a relative transverse movement between the broom holder and needle, of an oscillatory thread carrier adapted to carry a thread over the needle and into the eye thereof while moving rearwardly toward the unsewed portion of the broom.

2. In a broom sewing machine, the combination of a pivotally mounted broom holder, a needle adapted to be reciprocated through a broom in said holder and having adjacent its free end an eye that opens upwardly, means for intermittently moving the broom holder about its pivot, past the needle, and a movable thread carrier adapted to engage a thread at a point in rear of the needle to be threaded and carry such thread over the needle and into the eye thereof while moving rearwardly toward the unsewed portion of the broom.

3. In a broom sewing machine, the combination with a broom holder, and needles adapted to be reciprocated through a broom in said holder from opposite sides thereof, said parts being arranged to permit a relative transverse movement between the broom and needles, of a pair of oscillatory thread carriers mounted on opposite sides of the broom holder and each adapted to withdraw the thread from the needle mounted on the same side of the broom holder and to carry the thread engaged thereby into the eye of the other needle as the latter is projected across the broom holder and while said carrier is moving toward the unsewed portion of the broom.

4. In a broom sewing machine, the combination of a pivotally mounted broom holder, a needle adapted to be reciprocated through a broom in said holder, means for intermittently moving the broom holder about its pivot, past the needle, an oscillatory thread

carrier having an eye, through which the needle passes, a clamping finger or arm, pivoted to turn about the same axis as the body of the carrier and movable across said eye, and a spring acting to hold said finger across the eye in position to clamp the thread, and a stop arranged in the path of said finger and adapted to cause the same to be held away from said eye during a portion of each turning movement of the carrier, while the needle is passing through the eye of the carrier.

5. In a broom sewing machine, the combination of a pivotally mounted broom holder, a needle adapted to be reciprocated through a broom in said holder, means for intermittently moving the broom holder about its pivot, past the needle, an oscillatory thread carrier having an eye, through which the needle passes, a finger or arm pivotally mounted at an intermediate point in its length in a slot or socket in the carrier and adapted to swing to and from a position across said eye, a spring acting to hold said finger across the eye of the carrier, and a stop mounted on the frame of the machine, in the path of said finger as the carrier is turned about its axis, substantially as and for the purpose described.

6. In a broom sewing machine, the combination with a pivotally mounted vise, suitable needles and thread carriers, and a vertically movable broom support arranged within the vise and having a rack connected therewith, of a single pawl adapted to engage said rack to control the vertical position of the broom support, and means for disengaging said pawl from the rack prior to the formation of the first stitch in a row of stitches and causing it to reengage a higher tooth of the rack at the completion of the row of stitches.

7. In a broom sewing machine, the combination with suitable sewing mechanism, a pivotally mounted broom holding vise, means for rocking the vise about its pivot, and a vertically movable broom support arranged within the vise and having a rack connected therewith, of a pawl normally engaging said rack, means connected with the pawl and adapted to disengage it from the rack prior to the formation of the first stitch in a row of stitches, and means for causing the pawl to reengage the next highest tooth of the rack after the completion of said row of stitches.

8. In a broom sewing machine, the combination with suitable sewing mechanism, a pivotally mounted broom holding vise, means for rocking the vise about its pivot, and a vertically movable broom support arranged within the vise and having a rack connected therewith, of a single pawl mounted on the vise and adapted to engage the rack to control the vertical position of the

broom support, a spring acting to hold the pawl in engagement with the rack and means for positively disengaging the pawl from the rack as the vise is adjusted to position 5 to begin a row of stitches, said spring causing reengagement of the pawl and rack as the step-by-step movements of the vise for each row of stitches is completed.

9. In a broom sewing machine, the combination with suitable sewing mechanism, a 10 pivotally mounted broom holding vise, means for rocking the vise about its pivot, and a vertically movable broom support arranged within the vise and having a rack 15 connected therewith, of a pawl mounted on the vise and adapted to engage the rack, a spring acting to hold the pawl in engagement with the rack, and a stop on the machine frame adapted to disengage the pawl 20 and rack as the vise moves to position for commencing a row of stitches.

10. In a broom sewing machine, the combination with suitable sewing mechanism, a pivotally mounted broom holding vise, 25 means for rocking the vise about its pivot, and a vertically movable broom support arranged within the vise and having a rack connected therewith, of a pawl mounted on the vise and adapted to engage the rack, a 30 lever fulcrumed on the vise and having one member engaging said pawl, a spring acting to hold the pawl in engagement with the rack, and a stop on the machine frame in the path of said lever, as the vise moves to position 35 for commencing a row of stitches, whereby the pawl will be disengaged from the rack prior to the formation of the first stitch.

11. In a broom sewing machine, the combination with suitable sewing mechanism, a 40 pivotally mounted broom holding vise, means for rocking the vise about its pivot, and a vertically movable broom support arranged within the vise and having a rack 45 connected therewith, of a pawl mounted on the vise and adapted to engage the rack, a spring acting to hold the pawl in engagement with the rack, a lever fulcrumed on the vise and having a loose connection at 50 one end with said pawl, and a stop on the machine frame adapted to rock said lever to disengage the pawl from the rack as the vise is rocked to position to commence a row of stitches.

55 12. In a broom sewing machine, the combination with a suitable vise, needles, the vise being adapted to move transversely of the path of the needles, and a vertically movable broom support arranged within the 60 vise and having a rack connected therewith, of a pawl movable toward and from said rack and adapted to engage the several teeth thereof to support the broom support at different elevations, and means for disengaging the pawl from the rack prior to the for-

mation of the first stitch in a row of stitches without opening the vise, said pawl being caused to reengage a higher tooth of rack at the completion of a row of stitches.

13. In a broom sewing machine, the combination with suitable sewing mechanism, a 70 pivotally mounted broom holding vise, adapted to be rocked about its pivot during the formation of each row of stitches, a vertically movable broom support having a rack connected therewith, and a pawl normally engaging said rack, of means controlled by the movement of the vise about its pivot for disengaging said pawl and rack prior to the completion of a row of stitches 75 and causing the reengagement thereof at a higher point on the rack at the completion of a row of stitches.

14. In a broom sewing machine, the combination with suitable sewing mechanism, a 80 pivotally mounted broom holding vise, adapted to be rocked about its pivot during the formation of each row of stitches, a vertically movable broom support having a rack connected therewith, and a pawl normally engaging said rack, of means controlled by the movement of the vise about its pivot for disengaging said pawl and rack prior to the formation of the first stitch in a 85 row of stitches and causing the reengagement thereof at a higher point on the rack at the completion of a row of stitches.

15. In a broom sewing machine, the combination with suitable sewing mechanism, a pivotally mounted broom holding vise, 90 adapted to be rocked about its pivot during the formation of each row of stitches, a vertically movable broom support having a rack connected therewith, and a pawl normally engaging said rack, of means controlled by the movement of the vise about its pivot for disengaging said pawl and rack prior to the formation of the first stitch in a 95 row of stitches and causing the reengagement thereof at a higher point on the rack at the completion of a row of stitches.

16. In a broom sewing machine, the combination with suitable sewing mechanism, a pivotally mounted broom holding vise, 100 adapted to rock about its pivot during the formation of each row of stitches, a vertically movable broom support having a rack connected therewith, and a pawl normally engaging said rack, of means adapted 105 to be automatically actuated by each complete oscillatory movement of the vise about its pivot to effect a disengagement of said rack and pawl and reengagement thereof at a higher point on the rack.

110 16. In a broom sewing machine, the combination with suitable sewing mechanism, a pivotally mounted broom holding vise, adapted to rock about its pivot during the formation of each row of stitches, a vertically movable broom support carried by the vise, and devices mounted on the vise and broom support and normally in engagement to hold the broom support at any of several elevations, of means whereby each complete oscillatory movement of the vise about its pivot causes the disengagement of said devices and a reengagement thereof in a different relation, for the purpose described.

17. In a broom sewing machine, the combination with suitable sewing devices, a vise movable relative to the sewing devices during the formation of a row of stitches, and a broom support carried by the vise and adapted to be adjusted vertically between 115 120 125 130

successive rows of stitches, of means controlling such vertical adjustment of the broom support and adapted to effect each of said adjustments by a plurality of vertical movements, one of which occurs while the vise is closed and the broom support held stationary thereby.

18. In a broom sewing machine, the combination with a vise, and a broom support carried by and adapted to be adjusted vertically relative to the vise, of a rack connected with the broom support, means on the vise coöperating with the rack to hold the broom support at the desired elevation, and means

15 for causing a relative movement between said rack and holding means to vary the position of the broom support, a portion of such movement being effected while the broom support is held stationary by the vise.

20 19. In a broom sewing machine, the combination with a vise, and a broom support carried by and adapted to be adjusted vertically relative to the vise, of a rack connected with the broom support and capable of a 25 limited movement longitudinally thereof, means on the vise adapted to engage the rack to hold the broom support at the desired elevation, and means adapted to cause the rack to move relatively to the broom sup-

30 port and said holding means while the vise maintains the broom support stationary and to cause a relative movement between the holding means and the rack and broom support when the latter is released by the opening of the vise.

20. In a broom sewing machine, the combination with suitable sewing mechanism, and a vise mounted to rock about a horizontal axis past the sewing mechanism, of 40 means for imparting a step-by-step movement to the vise including a relatively stationary abutment, and an intermittently movable sliding bar, an adjustable spacing device arranged between said abutment and 45 bar, and means for automatically varying the length of said spacing device in accordance with the thickness of the broom in the vise.

21. In a broom sewing machine, the combination with suitable sewing mechanism, and a vise mounted to rock about a horizontal axis past the sewing mechanism, of 50 means for imparting a step-by-step movement to the vise including an intermittently movable sliding bar, an adjustable stop for limiting the movement of said bar, and means for automatically adjusting said stop to vary the extent of movement allowed said bar in accordance with the thickness of the 55 broom in the vise.

22. In a broom sewing machine, the combination with suitable sewing mechanism, and a vise mounted to rock about a horizontal axis past the sewing mechanism, of 60 means for imparting a step-by-step move-

ment to the vise including an intermittently movable sliding bar, a lever bearing against a jaw of the vise and adapted to move therewith toward and from the other vise jaw, and a stop for determining the extent of 70 movement of the sliding bar connected with said lever, whereby the length of the step-by-step movements of the vise will be varied in accordance with the thickness of the broom in the vise.

23. In a broom sewing machine, the combination with suitable sewing mechanism, and a vise mounted to rock about a horizontal axis past the sewing mechanism, of 80 means for imparting a step-by-step movement to the vise including an intermittently movable sliding bar, a lever bearing against a jaw of the vise and adapted to move therewith toward and from the other vise jaw, and a stop for determining the extent of 85 movement of the sliding bar, said stop including an adjustable member adapted to vary the length of the stop, and connections between said adjustable member of the stop and said lever, whereby the length of the 90 stop will be changed and the extent of movement permitted the sliding bar varied in accordance with the thickness of the broom in the vise.

24. In a broom sewing machine, the combination with suitable sewing mechanism, and a vise mounted to rock about a horizontal axis past the sewing mechanism, of 95 means for imparting a step-by-step movement to the vise including an intermittently 100 movable sliding bar, a lever bearing against a jaw of the vise and adapted to move therewith toward and from the other vise jaw, and a stop for determining the extent of movement of the sliding bar, and having at 105 its free end a rotatable section bearing against a cam surface on the body of the stop, and connections between said rotatable section of the stop and said lever whereby 110 said section will be turned and the length of the stop varied in accordance with the extent to which the vise is closed.

25. In a broom sewing machine, the combination with suitable sewing mechanism, a pivotally mounted broom holding vise, 115 adapted to be rocked about its pivot during the formation of each row of stitches, a vertically movable broom support having a rack connected therewith, and a pawl normally engaging said rack, of means controlled by 120 the movement of the vise about its pivot for automatically disengaging the pawl and rack and effecting a reengagement thereof at a higher point on the rack, whereby the 125 broom support is caused to move vertically relative to the vise between the formation of successive rows of stitches.

26. In a broom sewing machine, the combination with suitable sewing mechanism, a vise movable transversely of the sewing 130

mechanism, a vertically movable broom support mounted in the vise, a rack, and a pawl coöperating with the rack, one of said coöperating elements being connected with the vise and the other with the broom support in such manner that when disengaged there will be a relative movement between them in the direction of the length of the rack, of means for disengaging the pawl and rack while the vise is closed.

27. In a broom sewing machine, the combination with suitable sewing mechanism, a vise movable transversely of the sewing mechanism, a vertically movable broom support mounted in the vise, a rack, and a pawl coöperating with the rack, one of said coöperating elements being connected with the vise and the other with the broom support in such manner that when disengaged there will be a relative movement between them in the direction of the length of the rack, of means actuated by the movements of the vise transversely of the sewing mechanism for disengaging the pawl and rack while the vise is closed.

28. In a broom sewing machine, the combination with suitable sewing mechanism, a vise movable transversely of the sewing mechanism, a vertically movable broom support mounted in the vise, a rack, and a pawl coöperating with the rack, one of said coöperating elements being connected with the vise and the other with the broom support in such manner that when disengaged there will be a relative movement between them in the direction of the length of the rack, of means actuated by the movements of the vise transversely of the sewing mechanism for disengaging the pawl and rack while the vise is closed, said pawl and rack being restored to normal relation with each other and the broom support when the vise is opened.

29. In a broom sewing machine, the combination with suitable sewing mechanism, a pivotally mounted broom holding vise, adapted to be rocked about its pivot during the formation of each row of stitches, and a vertically movable broom support having a rack connected therewith, of a pawl having its upper end connected with the vise and its lower end provided with a tooth adapted to engage the rack, and means controlled by the movement of the vise about its pivot for causing said pawl to successively engage and disengage the rack, for the purpose described.

30. In a broom sewing machine, the com-

bination with suitable sewing mechanism, a pivotally mounted broom holding vise 60 adapted to be rocked about its pivot during the formation of each row of stitches, and a vertically movable broom support, of a rack connected with the broom support and movable longitudinally relative thereto, a 65 pawl normally engaging the rack, and means for disengaging the pawl and rack and permitting the latter to move longitudinally relative to the pawl and broom support while the vise is closed, the pawl 70 and rack being reengaged at a different point when the vise is opened.

31. In a broom sewing machine, the combination with suitable sewing mechanism, a pivotally mounted broom holding vise 75 adapted to be rocked about its pivot during the formation of each row of stitches, and a vertically movable broom support, of a rack connected with the broom support and movable longitudinally relative thereto, a 80 pawl normally engaging the rack, and means controlled by the movement of the vise about its pivot for disengaging the pawl and rack and permitting the latter to move longitudinally relative to the pawl 85 and broom support while the vise is closed, the pawl and rack being reengaged at a different point when the vise is opened.

32. In a broom sewing machine, the combination with suitable sewing mechanism, a 90 broom holding vise movable transversely of the sewing mechanism, and a vertically movable broom support arranged within the vise, of a rack, a hanger supporting said rack and having at its upper end separated 95 lugs extending above and below a rib on the broom support, the space between the lugs being greater than the thickness of the rib, a pawl mounted on the vise and normally engaging the rack and holding the 100 latter in such position that its hanger engages the lower side of said rib, and means for disengaging the pawl and rack while the vise is closed, to permit the rack to move downwardly until its hanger engages the 105 upper face of said rib, the pawl being reengaged with the rack and the hanger thereof restored to its normal position relative to the vise when the latter is opened.

In testimony whereof we affix our signatures in presence of two witnesses.

CHARLES E. OYLER.

JOHN HENRY PARKER.
